UNITED STATES PATENT OFFICE.

JACK B. KABANUCK, OF MAX, NORTH DAKOTA.

PISTON-RING REMOVER.

Application filed March 27, 1922. Serial No. 547,051.

To all whom it may concern:

Be it known that I, JACK B. KABANUCK, citizen of the United States, residing at Max, in the county of McLean and State of North Dakota, have invented certain new and useful Improvements in Piston-Ring Removers, of which the following is a specification, reference being had to the accompanying drawings.

10 This invention relates to improvements in piston ring removers, and more particularly to a device for expanding piston rings to remove the same from the grooves in which they operate.

15 An important object of the invention is to provide in a device of this character means whereby the amount of expansion which is imparted to the piston ring may be accurately gauged, whereby to prevent breakage of the ring and removal thereof.

20 A further object of the invention is to provide a device of this character which is simple in construction and operation, durable in service, and a general improvement in the art.

25 These and other objects I attain by the construction and arrangement shown in the accompanying drawings wherein for the purpose of illustration is shown a preferred embodiment of my invention and wherein like reference characters designate like parts throughout.

In the drawings:

30 Figure 1 is a side elevation showing a piston ring remover constructed in accordance with my invention in position to receive a piston preparatory to removing the rings therefrom; and

35 Figure 2 is a similar view showing the remover in the closed position and the ring expanded.

40 Referring now more particularly to the drawings, the numeral 10 indicates a pair of plier connected members, the jaw ends 45 11 of which have secured to their extremities oppositely extending diverging members 12, in the present instance shown as curved so as to admit a piston therebetween. To the ends of the diverging portions 12 are pivotally connected, as at 13, levers 14, the ends 50 of which are curved, as indicated at 15, and provided with hooks 16 for engaging the edges of the piston ring at the split thereof, these ends 15 being preferably slightly elastic. To the opposite ends of the levers 14

links 17 have one end pivotally connected, the opposite ends of these links being pivotally connected with the operating ends of the plier members 10, as indicated at 18. 60

It will be seen that as the jaws are opened the levers 14 will be simultaneously separated at their pivot points and caused to rock about their pivot points by the link connection 17, this connection being spaced from the pivot point 10^a of the plier members a distance greater than the distance from the pivot point to the ends of the jaw members 11, and the hook portions 16 of the levers 14 are caused to approach one another. 70 With the jaws open the piston may be inserted intermediate the jaws and the hooked ends 16 of the levers 14 engaged in the split of the piston ring and against the edges of the walls of the split. The handle portions 75 of the plier members being moved toward one another, the hook portions 16 are separated, expanding the piston ring and enlarging the same sufficiently to permit its removal from the groove. The opposite movement of the pivotal connection of the levers 14 and the movement imparted by the link connection prevents the movement of the member 16 being too rapid. Where the movement is rapid there will be a tendency 80 to slip and accordingly this feature has been found to be of decided advantage. 85

In order to normally maintain the jaws 11 in the open position, between the handle portions of the plier members 10, a spring 90 19 is inserted and in order that the rings may not be opened to such an extent as to destroy their resiliency and fit within the piston or to break the same, a set screw 20 is adjustably mounted in one of the handle 95 portions of the plier members and is adapted to engage against the other of such handle portions to limit the movement.

From the foregoing it is believed to be obvious that a piston ring remover constructed in accordance with my invention is particularly well adapted for the use for which it is intended by reason of the fact that means are provided for gradually expanding the ring and for adjusting the movement of the expansion members to prevent over expansion of the ring. It will furthermore be obvious that the construction as hereinbefore set forth is capable of some change and modification without materially departing from the spirit of my in- 100 105 110

vention and I accordingly do not limit myself thereto except as hereinafter claimed.

I claim:

1. In a piston ring remover, a pair of plier connected members, divergent members secured to the ends of the jaw portions of the plier members, levers pivotally connected to the ends of the divergent portions and each provided at one end thereof with a hook adapted to engage in the slot of the piston ring, and links pivotally connected to the free ends of said levers and to the handle portions of the plier members.
2. In a piston ring remover, a pair of plier connected members, divergent members secured to the ends of the jaw portions of the plier members, levers pivotally connected to the ends of the divergent portions and each provided at one end thereof with a hook adapted to engage in the slot of the piston ring, and links pivotally connected to the free ends of said levers and to the handle portions of the plier members, the pivotal connection of said links with the handle portions of the plier members being at a point spaced from the pivotal connection of the plier members a distance greater than the distance from the pivotal connection to the point of attachment of the divergent members 12.
3. In a piston ring remover, a pair of plier connected members, divergent members secured to the ends of the jaw portions of the plier members, levers pivotally connected to the ends of the divergent portions and each provided at one end thereof with a hook adapted to engage in the slot of the

piston ring, links pivotally connected to the free ends of said levers and to the handle portions of the plier members, and a spring 40 extending intermediate the handle portions of said plier members.

4. In a piston ring remover, a pair of plier connected members, divergent members secured to the ends of the jaw portions of the plier members, levers pivotally connected to the ends of the divergent portions and each provide at one end thereof with a hook adapted to engage in the slot of the piston ring, links pivotally connected to the free ends of said levers and to the handle portions of the plier members, and a set screw 45 adjustably mounted in the handle portion of one of said plier members and adapted to engage the other of said plier members.

5. In a piston ring remover, a pair of plier connected members, divergent members secured to the ends of the jaw portions of the plier members, levers pivotally connected to the ends of the divergent portions and each provided at one end thereof with a hook adapted to engage in the slot of the piston ring, links pivotally connected to the free ends of said levers and to the handle portions of the plier members; a set screw 60 adjustably mounted in the handle portion of one of said plier members and adapted to engage the other of said plier members, and means for normally holding the jaw portions of the plier members in the open 65 position.

In testimony whereof I hereunto affix my signature.

JACK B. KABANUCK.
